UNITED STATES PATENT OFFICE.

BENJAMIN BENJAMIN, OF CHICAGO, ILLINOIS.

DESIGN FOR A BOTTLE.

Application filed September 25, 1926. Serial No. 19,178. Term of patent 7 years.

To all whom it may concern:

Be it known that I, BENJAMIN BENJAMIN, a citizen of the United States, residing at 1901 West Roosevelt Road, city of Chicago, Ill., in the county of Cook and State of Illinois, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

BENJAMIN BENJAMIN.
